LINE GUIDE FOR FISHING RODS

Joseph F. Filo, Jr., Bridgeport, Conn.

Application March 20, 1948, Serial No. 145,244

Term of patent 7 years

(Cl. D31—4)

To all whom it may concern:

Be it known that I, Joseph F. Filo, Jr., a citizen of the United States, residing at Bridgeport, county of Fairfield, State of Connecticut, have invented a new, original, and ornamental Design for Line Guide for Fishing Rods, of which the following is a specification; reference being had to the accompanying drawing, forming part thereof.

Fig. 1 is a perspective view of a line guide for fishing rods, showing my new design;

Fig. 2 is a top plan view thereof;

Fig. 3 is a side elevation, and

Fig. 4 is an end view.

I claim:

The ornamental design for a line guide for fishing rods, substantially as shown.

JOSEPH F. FILO, JR.
